EDGAR M. BOUTON, OF PARK RIDGE, ILLINOIS, ASSIGNOR TO WESTINGHOUSE ELECTRIC
ELEVATOR COMPANY, A CORPORATION OF ILLINOIS

GATE AND DOOR SEQUENCE

Application filed December 20, 1922. Serial No. 415,458.

My invention relates to elevator doors and gates and more particularly to the mechanism employed for opening and closing such doors and gates.

5 In various installations of automatic elevators; that is, elevators arranged to be operated by the passengers instead of by car attendants, the corridor doors and the elevator gates are provided with means for biasing them toward their closed positions so that they will close when they are not held open. Usually, the doors and gates are also provided with checking devices that cause them to move slowly during the latter part of their 10 closing movements so that they will close gently.

In elevators provided with closing devices of the character indicated when a passenger desires to get on the car, it is necessary for 20 him to open both the corridor door and the car gate and hold both of them open while he enters the car. In leaving the car, the passenger must open both the gate and door and hold them open while he makes his exit therefrom. In many instances, the passengers are burdened with bundles or packages which 25 make it awkward for them to hold both the door and the gate while entering or leaving the car.

30 Therefore, it is an object of my invention to provide for causing the corridor door, when moved to its open position, to remain in that position until the car gate is closed in order to relieve the passenger of the necessity 35 of simultaneously holding both the door and the gate in their open positions.

It is also an object of my invention to provide means by which the passenger, after entering the car, may control the action of the 40 gate-checking device in such manner that the gate will close as quickly as possible and thereby effect a prompt closing of the corridor door.

45 Other objects of my invention will, in part, be obvious and will, in part, appear herein-after.

For an illustration of one of the various forms my invention may take, reference may be had to the accompanying drawing, in 50 which;

Figure 1 is a diagrammatic representation of an elevator gate and a corridor door that are provided with operating mechanism constructed in accordance with my invention; and

55

Fig. 2 is an enlarged view of the operating mechanism for the gate shown in Fig. 1.

In the drawing, I have illustrated an elevator car door or gate 1 as disposed adjacent to a corridor door 2, when viewed from the interior of an elevator car (not shown).

The car door or gate 1 is shown as being of the collapsible type that is mounted upon the door frame 3 of the car by means of a plurality of rollers 4 in such manner that it may 60 be readily moved into a collapsed position at one side of the doorway by a passenger when he desires to enter or leave the car.

An actuating device 5 is provided for biasing the door or gate 1 to a closed position so, 70 that it will close when it is not being held open. The actuating device 5 comprises a cylinder 6, a piston 7 that is disposed to operate in the cylinder and a compression spring 8 for operating the piston. The 75 spring 8 is mounted upon a rod 9 in a compressed position between the upper head of the cylinder 6 and the head of the piston 7. The position of the compressed spring causes it to exert a force upon the piston head 7 80 that tends to pull the piston rod 9 into the cylinder 6.

The lower end of the cylinder 6 is pivotally connected to a bracket 10 on the gate frame 3, while the free end of the piston rod 9 is 85 pivotally attached to a gate-moving arm comprising a pair of pivotally-connected links 11 and 12. The free end of the link 11 is pivotally attached to a bracket 17 on the gate frame 3, and the free end of the link 12 is 90 pivotally attached to the outer end of the gate 1 in such manner that a pull exerted upon the link 11 by the piston rod 9 will cause the links to straighten out and thereby move the gate to its closed position. A 95 handle 13 is attached to the gate for the use of the passengers in opening the gate.

The piston 7 is constructed to neatly fit the cylinder 6 so that it will act as dashpot when the gate 1 is closing and thereby retard 100

the final closing movement of the gate in such manner that it will come gently to rest in its closed position. A suitable vent hole 15 is provided in the cylinder 6 to diminish the retarding action of the dashpot during the first portion of the closing movement until the piston has passed the vent 15. Also, a suitable inlet valve 16 is mounted in the lower end of the cylinder 6 to permit air to enter freely when the piston is moving upwardly, in order to enable the gate to be opened as easily as possible, but which closes when the piston is moving downwardly to restrict the passage of air from the cylinder and thus check the speed of the gate.

15 As shown, the corridor door 2 for closing the entrance from the floor landing to the elevator shaft is constructed in three sections that are adapted to slide into and out of a closed position in the door frame 18.

20 Mounted in the free edge of the door 2 is a door-latching device 19 of the usual construction for automatically locking the door in its closed position. Inasmuch as such door-latching devices are old and well-known in the art, a detailed description thereof will not be given.

25 An actuating device 20 is provided for biasing the corridor door 2 to a closed position so that it will close when it is not held open by a passenger who desires to enter or leave the car.

30 The door-actuating device 20 comprises a cylinder 21, a piston 22 disposed therein and a compression spring 23 for operating the piston. The spring 23 is mounted on a piston rod 24 in a compressed position between the piston 22 and the upper end of the cylinder 21. In this position, the spring 23 exerts 35 a force upon the piston 22 that tends to pull the piston rod 24 into the cylinder 21.

35 The lower end of the cylinder 21 is pivotally mounted on a bracket 25 attached to the door frame 18, while the free end of the piston rod 24 is pivotally connected to a door-moving arm comprising a plurality of pivotally-connected links 27, 28 and 29. The link 28 is pivotally mounted on the middle section of the door 2, while the free end of the link 27 is pivotally mounted on a bracket 30 on the door frame 18, and the free end of the link 29 is attached to the outer section of the door 2. With this arrangement, the spring 23 exerts a pull upon the piston rod 24 which causes the links 27, 28 and 29 to straighten out and thereby move the door 2 to its closed position.

40 The piston 22 is designed to fit the cylinder 21 so snugly that it will act as a dashpot for checking the final closing movement of the door 2. A suitable exhaust port 45 may be provided in the cylinder 21 to so control the dashpot effect of the piston that the first portion of the door-closing movement may 45 be rapid until the piston passes the port. The

cylinder 21 may also be provided with a suitable checking inlet valve 46 to permit the door 2 to be opened as easily as possible, and to regulate the checking action in the final stages of the closing movement.

45 In automatic-elevator installations embodying car gates and corridor doors of the above indicated character, it is necessary for the passengers to open both the gate and the corresponding corridor door and hold them open while they enter or leave the car. In many instances when a passenger is carrying packages or bundles it will not be easy for him to hold both the gate and door as he enters or leaves. Therefore, I have provided a door-holding means that will automatically cause the corridor door to remain open after it is opened until the car gate is subsequently closed.

50 The door-holding means comprises a latch 34 for holding the door, an electromagnet 35 for releasing the latch and a switch 36 that is operably responsive to the closing of the car gate for completing a circuit to energize the electromagnet.

55 The latch 34 is pivotally mounted on a bracket 37 on the door frame 18 in such position that it will engage a projection 38 on the door-operating link 27 when the door is moved to its open position. When the projection 38 is caught by the latch 34, the link 27 cannot be moved downwardly to close the door until the electromagnet 35 is energized to raise the latch.

60 The switch 36 for energizing the electromagnet 35 to raise the latch comprises an insulating base 39 provided with a stationary contact member 40 and a movable contact member 41. The switch 36 is suitably mounted at the corridor door in such position that the movable contact member projects toward the car gate 1. The movable contact member 41 is pivotally mounted on the base 39 in such position that it will be moved into engagement with the stationary contact member 40 by a projection 32 on the gate 1 when the gate is moving to the closed position. As shown, when the contact members 40 and 41 are closed by the closing of the gate 1, a circuit is completed for energizing the electromagnet 35 to lift the latch 34 from the projection 38 to permit the door 2 to close under the force of the door-actuating device 20. Although the movable contact member 41 will be moved by the projection 32 when the gate 1 is opened, its position permits it to then swing away from, instead of toward, the stationary contact member 40. Therefore, the opening of the gate will not effect the circuit for the electromagnet 35.

65 Under some circumstances a passenger who has boarded the elevator car may desire the car gate 1 to close more rapidly than usual under the action of the gate-actuating device 5. Therefore, I have provided the cylinder

6 of the gate-actuating device 5 with an additional exhaust port 47 which may be opened to exhaust the cylinder rapidly and thereby permit the car gate to close more quickly than usual.

5 The exhaust port 47 is controlled by a valve 48 that is operated by an electromagnet 49. The operation of the electromagnet 49 is controlled by a push-button switch 50 on the gate frame 3 so that a passenger may operate the push button to cause the exhaust port 47 to open when he desires the gate to close quickly.

The operation of the device is as follows:

Assuming that a car is standing at a floor landing with its gate 1 disposed opposite the corridor gate 2, and that a passenger in the corridor, desiring to enter the car, operates the door handle 19 to unlock the door 2, and move it to an open position, then the opening movement of the door 2 causes the door-operating links 27, 28 and 29 to move into their retracted position. In such retracted position, the projection 38 on the link 27 is caught by the door-holding latch 34, as shown by broken lines, and thus the door is retained in its open position. Therefore, the passenger does not need to hold the door open. The upward movement of the link 27 exerts a pull upon the piston rod 24 which places the spring 23 under compression, thereby storing up energy that will cause the door to move to its closed position when the latch 34 is released.

Assuming now that the passenger grasps the gate handle 13 and moves the gate 1 to its open position, then the movement of the gate causes the gate-operating arm, comprising the links 11 and 12, to fold up. The upward movement of the link 11 exerts a pull upon the piston rod 9 which compresses the spring 8 and thereby stores up energy that will cause the car gate to close as soon as it is released by the passenger.

Assuming now that the passenger is in the car and releases the car gate 1, then the stored up energy in the spring 8 of the gate-actuating device 5 exerts a pull upon the piston rod 9 which, in turn, operates the links 11 and 12 to move the gate to its closed position. As the gate approaches its closed position, the piston head 7 moves downwardly in the cylinder 6 and the dashpot action thereof slows up the closing movement of the gate.

Assuming that the passenger, being in a hurry and desiring to have the car gate close as quickly as possible, presses the push button 50, then a circuit is completed for energizing the electromagnet 49 which circuit extends from a supply conductor L1, through conductor 51, the coil of the electromagnet 49, conductor 52, the contact members of the push button 50 and conductor 53, to a supply conductor L2. The energization of the electromagnet 49 causes it to pull the valve 48 from the exhaust port 47, thereby releasing the air

in the cylinder 6 to permit the free action of the piston 7 and operation of the compressed spring 8 to close the gate quickly.

As the gate 2 closes, the projection 32 thereon engages the movable contact member 41 on the switch 36 and moves it into engagement with the stationary contact member 40, thereby completing a circuit for energizing the electromagnet 35, which circuit extends from the supply conductor L1, through conductor 55, the coil of the electromagnet 35, conductor 56, the stationary contact member 40, the movable contact member 41 and conductor 57, to the supply conductor L2.

The energization of the electromagnet 35 causes it to raise the door-holding latch 34 and thereby release the projection 38. The release of the projection 38 permits the link 27 to move downwardly under the operation of the door-actuating device 20 and thereby effects the closing of the door 2. As the door 2 approaches its closed position, under the force exerted by the spring 23, the piston 22 reaches the lower part of the cylinder 21 and thereby acts as a door check to slow up the closing movement of the door and cause it to come gently to rest in its closed position.

While I have, for the sake of simplicity, shown the passenger-controlled release valve as applied only to the gate-actuating device 5 to enable passengers to control the closing speed of the gate, a similar release valve may be applied to the door-actuating device 20 for controlling its closing speed, if desired.

Therefore, it will be seen that I have provided a door-and-gate-operating mechanism for use in automatic elevators that will permit the passengers thereon to operate the doors and gates with a minimum amount of effort and to also control the closing speed of the doors and gates.

While I have illustrated and described only one specific embodiment of my invention, I realize that it is susceptible of many applications and I do not desire to be limited to the precise construction shown and described.

I claim as my invention:

1. In an elevator system, a pair of doors, means for retaining one of said doors in its open position, and means operably responsive to a closing movement of the other of said doors for operating said retaining means to release the retained door.

2. In an elevator system, a pair of cooperating doors, means for biasing said doors to their closed positions, means for retaining one of said doors in its open position when it is moved to said open position, and means operably responsive to the closing of the other of said doors for operating said retaining means to permit the retained door to close.

3. In an elevator system, a pair of doors, means for biasing the doors to their closed positions, a latch for retaining one of said doors in its open position after it has been

opened, an electromagnet for releasing said latch, a circuit for said electromagnet, and a switch for controlling said circuit, said switch being disposed to be operated by the closing of the other of said doors to energize said electromagnet to release said latch.

4. In an elevator system, a car gate, means for biasing the gate to a closed position, a corridor door, means for biasing the corridor door to a closed position, means for retaining the corridor door in its open position, and means operably responsive to movement of the car gate for operating said retaining means to release said door.

5. In an elevator system, a pair of doors, means for retaining one of said doors in its open position, means operably responsive to a closing movement of the other of said doors for releasing the retained door, means for applying a predetermined checking effect to the closing movement of said other door, and means disposed to be operated by a passenger for decreasing the checking effect to permit said other door to close quickly.

6. In an elevator system, a pair of doors, means for retaining one of said doors in its open position, means operably responsive to a closing movement of the other of said doors for releasing the retained door, means for applying a predetermined checking effect to the closing movement of said other door, means disposed to be operated by a passenger for decreasing the checking effect to permit said other door to close quickly, and means for automatically returning the checking means to its predetermined setting after operation of the passenger operated means.

7. In an elevator system, a pair of co-operating doors, means for biasing said doors to their closed positions, means for retaining one of said doors in its open position when it is moved to said open position, means operably responsive to the closing of the other of said doors for operating said retaining means to permit the retained door to close, a dash-pot for applying a checking effect to the door as it closes, a valve for opening said dash-pot to permit said other door to close quickly, an electromagnet for opening said valve, a circuit for said electromagnet and a switch connected in said circuit and disposed to be operated by a passenger for controlling the operation of said electromagnet.

In testimony whereof, I have hereunto subscribed my name this 9th day of December, 1929.

EDGAR M. BOUTON.
